UNITED STATES PATENT OFFICE.

ORION WISER AND ARLIE KEMPER, OF MARTINSVILLE, ILLINOIS.

COLLAPSIBLE EGG CRATE.

Application filed August 25, 1924. Serial No. 734,024.

To all whom it may concern:

Be it known that we, ORION WISER and ARLIE KEMPER, citizens of the United States, both residing at Martinsville, in the county 5 of Clark and State of Illinois, have invented certain new and useful Improvements in Collapsible Egg Crates; and we do hereby declare the following to be a full, clear, and exact description of the invention, such 10 as will enable others skilled in the art to which it appertains to make and use the same.

This invention relates to improvements in collapsible egg crates of such construction 15 that the crates when not in use can be folded into a compact shape. Various features of novelty and invention will appear from the detailed description taken in connection with the accompanying drawings forming part 20 of the specification.

Referring to the drawings, Fig. 1 is a perspective view showing the crate folded.

Fig. 2 is a view in side elevation of the 25 crate set up.

Fig. 3 is a longitudinal section through the 30 crate as shown in Fig. 2.

Fig. 4 is a transverse section through the 35 folded crate.

Fig. 5 is a top plan view of one end of 40 the crate.

Fig. 6 is a perspective view of one corner 45 of the crate.

Fig. 7 is a perspective view showing one 50 step in the method of setting up the crate from its folded position.

Fig. 8 is a view similar to Fig. 7 showing 55 another step in the setting up of the crate.

Fig. 9 shows the crate completely set up 60 with the cover open; and

Fig. 10 is a perspective view of the 65 interior of the set up crate, showing the partitions therein.

The improved crate is a rectangular member having a pan-like bottom struck up from 70 sheet metal, the bottom proper being indicated by numeral 1, the side flanges thereof by 2 and 3, and the end flanges by 4 and 5, respectively.

To the side flange 2 of the bottom is 75 hinged a side wall 6, the upper edge of the wall being turned inwardly to form a flange 7 for a purpose hereinafter mentioned.

To the other upright flange 3 of the bottom 80 1 is hinged a wall member 8 and to the

upper edge of this wall member is hinged 85 the top cover 9, the width of the same being somewhat less than the height of the wall 8 as is clearly shown in Fig. 4.

To the end flange 4 of the bottom 1 is hinged an end wall 10, and to the other flange 5 of the bottom is hinged the other end wall 11, both of these end walls having at their upper edge an inturned flange indicated by numeral 12 as regards the end wall 10 and 13 as regards the wall 11. The 90 side edges of the end walls 10 and 11 are also provided with inturned flanges 14 and 15, respectively.

It will be noted that the end flanges 4 and 95 5 of the bottom 1 are somewhat higher than the side flanges 2 and 3 thereof. This difference in height allows the side walls and top cover to lie in folded position, when the box is collapsed, in such manner that the end walls 10 and 11 may be disposed thereover 100 in a compact position as illustrated in Figs. 1 and 4. The hinges between the side and end walls and the bottom of the box are made by forming loops in the material through which are passed a hinge pin member in the form of a continuous piece of wire as indicated at 16.

From the construction thus far described 105 it will be seen that when the box is collapsed the side wall 8 will lie with one face disposed opposite the bottom of the box or crate and that the top member 9 will be turned back against the other side or face of the side 8, as clearly shown in Fig. 4. The other side wall 6 will be disposed over the 110 wall 8 and cover 9. The end walls 10 and 11 will rest on the side wall 6 as clearly shown in Figs. 1 and 4.

In order to hold the box in set up position, 115 the end walls 10 and 11 are connected by a link mechanism and a locking device now to be described. To the end wall 10 is rotatably secured a shaft 17 having crank arms 18 at each end, said shaft intermediate its ends being provided with a looped portion 19 forming a handle by means of which the shaft may be rotated. Pivots connected to each crank 18 of the shaft 17 is a comparatively short link 20 which, in turn, is pivotally connected as at 21 to a long link 22 which at its other end is pivotally connected as at 23 to a short link 24 which, in turn, is pivotally connected as at 25 to the side 120 125 130 135 140 145 150 155 160 165 170 175 180 185 190 195 200 205 210 215 220 225 230 235 240 245 250 255 260 flange 15 of the end wall 11. Referring to Fig. 2, it will be seen that the crank 18 is arranged at an acute angle to the loop 19 of the shaft so that when the loop 19 is disposed flush against the end wall 10 the end walls 10 and 11 are positively locked in position. When it is desired to collapse the box, the loop 19 is grasped to turn the shaft, thus allowing the end walls to turn outwardly a limited extent, this amount being sufficient to allow the box to be collapsed. By making the connection between the end walls 10 and 11 in the form of jointed links, said connection will offer no interference to the collapsibility of the box, as will be readily understood with reference to Fig. 1.

It has been pointed out that the end walls 10 and 11 are provided with side flanges 14 and 15, respectively. These side flanges constitute abutments against which the end edges of the side walls 6 and 8 abut when the box is in set up position. In other words, the said flanges 14 and 15 prevent the side walls of the box from moving outwardly. The side wall 6 when in upright position in addition to being held in such position by means of the flanges 14 and 15 on the end walls is also interlocked with the end walls by reason of the fact that a notch 26 is cut out in the flange 13 at the top of the end wall 11, as clearly indicated in Fig. 6. A similar notch is provided in the other upper corner of the end wall 11 to interlock with the other side wall 8. The other end wall 10 is provided with similar notches 26 for the same purpose. In view of the fact that the end walls 10 and 11 may be swung outwardly somewhat when the clamping mechanism previously described is released, the side and end walls can be readily interlocked by the cooperating means specified.

When the box is set up and closed, the cover 9 will be overlain at its end edges by the flanges 13 at the top edges of the end walls 10 and 11, and the top flange 7 on the side wall 6 will overlie the adjacent edge of the cover, as clearly shown in Fig. 5. In other words, the edges of the cover will be disposed below the inwardly extending flanges on the side and end walls. This arrangement effectually prevents the cover from opening outwardly when the box is set up. By merely releasing the locking mechanism, which is accomplished by turning the shaft 17, the parts will be sufficiently loosened to permit the cover 9 to be raised as by means of a handle in the form of a bail as indicated at 27 in Fig. 3.

When the improved box or crate is in knocked down position, the parts may be retained in that position as by means of a hook 28 and cooperating eye 29 secured to the end walls of the box, see Fig. 1. In case the box or crate is made heavy enough the same may be provided with lifting

handles as indicated at 30. It will be understood that the improved crate is not limited in size. The present construction is designed to hold thirty dozens of eggs, hence the provision of lifting handles 30.

70

In order to brace the side walls and to provide a plurality of compartments within the crate, there is provided a partition 31 which is hinged on a transversely extending pivot 32 which passes through and is secured to the side flanges 2 and 3 of the bottom 1. This partition is held in upright position preferably by means of bent out lugs 33 in the side walls 6 and 8. When the box is in knocked down position, the partition will lie against the bottom of the crate as shown in dotted lines in Fig. 3 and in cross section in Fig. 4.

80

In order to prevent the cover 9 from dropping down, there may be provided seats in the form of stamped out lugs 34 in the end walls of the box (see Figs. 3 and 6).

85

Figs. 7 to 10 are somewhat diagrammatic representations illustrating the manner in which the box is set up. Referring to Fig. 7, it will be seen that the end walls 10 and 11 are first raised to upright position; then the side wall 6 is swung in upright position between the end walls. Referring to Fig. 8, the side wall 8 is next swung into position, the top member 9 being first raised into the position shown in Fig. 8. The wall 8 is then swung into upright position as shown in Fig. 9. Thereafter, the partition 33 is raised and swung into position between the side walls 6 and 8 as will now be readily understood. Thereafter, the box is ready to be closed by turning the cover 9 on its hinges. After the box is set up, the clamping mechanism comprising the shaft member and links is closed as shown in Fig. 2. In order to knock down the box, the reverse operations are gone through with. That is to say, the clamping mechanism is released thereby permitting the ends of the box to be swung outwardly somewhat, the cover 9 is lifted up and turned back on its attached side wall, after which the other side wall 6 is turned over on top of the cover 9, and thereafter the end walls are folded down as shown in Fig. 1. The hook 28 is disposed over the various moving parts as shown in Fig. 1.

What is claimed is:

- In a knockdown box having its ends hinged to the bottom, means for drawing the ends toward each other comprising a crank lever mounted on one end of the box and means connecting said crank lever with the other end of the box.
- The structure specified in claim 1 in

which the means connecting the crank lever with the end of the box comprises a plurality of links.

3. In a knock down box, the combination of a bottom member having flanges extending therearound, side and end walls pivoted to said flanges, one of said side walls having a top member hinged to its upper edge, the other side wall having an inwardly turned flange along its upper edge, said end walls each having inwardly turned side flanges and an inwardly turned top flange, said side flanges serving as abutments to prevent the side walls from moving outwardly away from the end walls, and the top flanges on the end walls serving to confine the top member in position when the box is closed, and means for locking the box in set up position.

20 4. In a knock down box, the combination of a bottom member, of side and end walls hinged thereto, a top member hinged to one of the side walls, jointed links pivoted to one of said end walls and extending beyond the other end wall, and a crank shaft supported by that end wall beyond which said jointed links extend, the adjacent ends of said links being pivotally connected to said crank shaft, said crank shaft adapted to lock the box in set up position.

25 5. In a knock down box, the combination of a bottom member having flanges extending therearound, the end flanges being higher than the side flanges, end walls hinged to said end flanges, each end wall having an inwardly directed flange along its top edge and similarly directed flanges along its side edges, the top flange being shorter than the width of the end wall

whereby a notch is formed at the corners, 40 side walls pivoted to the side flanges of said bottom member, a top member pivoted to one of said side walls along the top edge of the latter, said side wall being of a height to enter the said notches in the said end 45 walls, said top member adapted to underlie when the box is closed the top flanges on the end walls and adapted when the box is knocked down to be folded back on its side wall, said side wall and top member adapted 50 to be received between the flanges extending around the bottom member, and means for locking said box in set up position.

6. In a knock down box, the combination of a bottom member, of side and end walls 55 hinged thereto, means between the end and side walls for locking the side walls against collapse, a crank shaft rotatably mounted on one of said end walls, and means extending between said crank shaft and the other end 60 wall, said means permitting the end wall to swing outwardly a limited extent.

7. In a knock down box, the combination of a bottom member having side flanges extending therearound, end and side walls pivoted 65 to said flanges, a cranked shaft rotatably mounted on one of said end walls, jointed members extending between the ends of said cranked shaft and the other end wall, said jointed means comprising a comparatively long intermediate link and shorter 70 links at the ends thereof which connect, respectively, with said shaft and the other end wall.

In testimony whereof we affix our signatures.

ORION WISER.
ARLIE KEMPER.
